United States Patent Office

Des. 227,483
Patented June 26, 1973

227,483

VIDEOTAPE RECORDER

Hari Matsuda, Evanston, Ill., assignor to International
Video Corporation, Sunnyvale, Calif.

Filed June 7, 1972, Ser. No. 260,715

Term of patent 14 years

Int. Cl. D14—01, 02

U.S. Cl. D26—14 B

FIG. 1.

FIG. 2.

FIG. 3.

FIG
4.FIG . 5.

FIG. 1 is a perspective view of a videotape recorder design with the retractable cover panels in the open position;

FIG. 2 is a perspective view of the videotape recorder design with the retractable cover panels in the closed position;

FIG. 3 is a front elevation view of the videotape recorder of FIG. 1;

FIG. 4 is a left side elevational view of the videotape recorder of FIG. 1. The right side elevational view is a mirror image of the view shown in FIG. 4;

FIG. 5 is a rear elevational view of the videotape recorder of FIG. 1.

I claim:

The ornamental design for a videotape recorder, as shown.
